DESIGN FOR A BOTTLE DISPLAY PACKAGE

Abraham Altman, Brooklyn, N. Y.

Application February 9, 1945, Serial No. 117,836

Term of patent 3½ years

(Cl. D80—5)

To all whom it may concern:

Be it known that I, Abraham Altman, a citizen of the United States, residing in Brooklyn, county of Kings, State of New York, have invented a new, original, and ornamental Design for a Bottle Display Package, of which the following is a specification, reference being had to the accompanying drawing, forming part thereof:

I claim:

The ornamental design for a bottle display package, as shown.

ABRAHAM ALTMAN.
